ROBERT LEE TAYLOR, OF MOUNT WASHINGTON, MARYLAND, ASSIGNOR OF ONE-FOURTH TO CHARLES A. BAUGHAN, OF CLIFTON FORGE, VIRGINIA.

SAFETY DEVICE FOR ELEVATORS.

1,087,560.

Specification of Letters Patent. Patented Feb. 17, 1914.

Application filed May 23, 1913. Serial No. 770,477.

To all whom it may concern:

Be it known that I, ROBERT L. TAYLOR, a citizen of the United States, residing at Mount Washington, in the county of Baltimore and State of Maryland, have invented a new and useful Safety Device for Elevators, of which the following is a specification.

The invention relates to improvements in safety devices for elevators.

The object of the present invention is to improve the construction of safety devices for elevators, and to provide a simple, practical and inexpensive safety device adapted to be readily applied to elevators, and capable in event of breakage of the cable or other flexible connection to which the car is attached of automatic operation and of instantly stopping the car without jarring the same or the occupants thereof.

With these and other objects in view, the invention consists in the construction and novel combination of parts hereinafter fully described, illustrated in the accompanying drawing, and pointed out in the claims hereunto appended; it being understood that various changes in the form, proportion, size and minor details of construction, within the scope of the claims, may be resorted to without departing from the spirit or sacrificing any of the advantages of the invention.

In the drawing:—Figure 1 is a vertical sectional view of a safety device for elevators, constructed in accordance with this invention, and shown applied to a car. Fig. 2 is a vertical sectional view, taken at right angles to Fig. 1 on the line 2—2 thereof. Fig. 3 is a horizontal sectional view on the line 3—3 of Fig. 1.

Like numerals of reference designate corresponding parts in all the figures of the drawing.

In the accompanying drawing in which is illustrated the preferred embodiment of the invention, 1 designates an elevator car movable vertically between opposite guides 2 having vertical channels 3 and provided thereon with racks 4, adapted to be engaged by dogs 5 of the car 1 in event of breakage of the cable 6, or other flexible connection to which the car is attached. The cable 6 is secured to an eye 7 of the upper end of a vertical rod 8, slideable through a top cross piece 9 or other suitable portion of the car

1 and secured at its lower end to a vertically movable horizontally disposed cross head 10. The lower end of the rod pierces the cross head and is threaded for the reception of nuts 11, the cross head being secured between the nuts and a collar 12, washers 13 being preferably arranged at the upper and lower faces of the cross head and interposed between the same and the nuts and the collar, but the vertical bar may be secured to the cross head 10 in any other suitable manner.

The cross head 10, which extends entirely across the car 1 at the upper portion thereof, has its ends arranged in vertical guides or ways, formed by spaced vertical bars or cleats 14 suitably secured to the frame of the car at the corners thereof, and the cross head is provided with corner recesses 15 to receive the vertical cleats or bars, but any other suitable means may be employed for 70 guiding the cross head.

When the cable 6 is subjected to the weight of the car, the cross head fits against the lower ends of the vertical stops or abutments 16, located above the cross head and preferably consisting of 80 vertical frame members extending downwardly from the top cross piece 9 and having their upper edges fitted against the same. By this arrangement, strong and secure means are provided for rigidly suspending the car from the cable. The lower engaging ends of the stops or abutments 16 extend a short distance below the upper ends of the guide cleats or bars 14, and the cross head 10 is movable downwardly from the 85 stops or abutments and in event of breakage of the cable 6 is adapted to move downwardly from the stops or abutments into contact with the dogs 5 to throw the same into engagement with the racks 4 to check 90

the car and prevent the same from dropping down the elevator shaft. The cross head 10 is adapted to drop by gravity into engagement with the dogs 5, but in order to insure a positive rapid downward movement of the said cross head and an instantaneous stopping of the car, a coiled spring 17 is disposed on the lower portion of the vertical rod 8 and is interposed between the top cross piece 9 and the movable cross head 10. The coiled spring 17 is compressed when the cross head 10 is at the limit of its relative vertical movement and in contact with the stops or abutments, which limit the upward movement of the said cross 105

head 10 and prevent the excessive pressure of the coiled spring 17 by relieving the same of the weight of the car. The cross head 10 when supporting the weight of the elevator car is located a comparatively short distance above the dogs 5, and the spring 17 is adapted to throw the cross head 10 downwardly and through the same to actuate almost instantly the dogs to secure 10 a quick stoppage of the car.

The dogs 5 are mounted on horizontal pivots 18 and operate in openings 19 of vertical slides 20, located at opposite sides of the car and arranged in vertical guides 21 thereof. The lower engaging ends of the dogs 5 are preferably beveled, as shown, and are adapted to be thrown outwardly into engagement with the teeth of the racks 4 by the cross head. The pivots 18 pierce 15 the dogs at the upper portions thereof, and the lower portions of the dogs are heavier than the upper portions and are adapted to maintain the dogs normally out of engagement with the racks through gravity. The 20 dogs are provided at their upper ends with inclined arms 22, extending upwardly and inwardly into the path of the cross head 10 and adapted to be engaged by the same. The upper walls 23 of the slots or openings 25 25 30 35 are inclined and extend upwardly and inwardly and form stops or abutments for the arms 22 and limit the downward and inward swing of the engaging portions of the dogs. The lower gravity acting portions of the dogs maintain the upper arms 22 normally in contact with the upper walls 23 of the slots or openings and in the path of the cross head 10.

The guides 21 consist of openings having 40 vertical grooves 24 in their opposite openings to receive tongues 25 of the slides, whereby the latter are slidably interlocked with the sides of the car. The upper ends of the vertical slides 20 are normally spaced 45 from the upper ends of the guides 21, and they are cushioned by coiled springs 26, mounted on vertical rods 27 and interposed between the upper end walls of the openings of the guides 21 and the upper ends of 50 the slides 20. The rods 27, which have their upper ends embedded in the sides of the car at the upper ends of the guides 21, extend downwardly in vertical bores or openings 28 of the slides 20. The coiled springs 26 55 are adapted to cushion the car and prevent jar of the same and the occupants thereof when the dogs 5 are thrown into engagement with the racks 4. Should the cable 6 break and release the cross head 10, the 60 latter would be instantly moved downwardly by the coiled spring 17 and would throw the dogs 5 into engagement with the racks 4, thereby stopping the car and prevent the same from dropping. When the 65 dogs engage the racks, the support of the

car is transferred from the cross head to the slides 20, and the coiled springs 26, which operate to cushion the car, prevent any jar or jolt and render the locking action hardly perceptible. In event of breakage of the 70 cable 6, the dogs 5 and their pivots 18 would be subjected to comparatively little strain when thrown into the racks 4 by the action of the cross head 10, owing to the cushioning action of the coiled springs 26 75 at the upper ends of the slides 20. This construction adds greatly to the safety of the device and eliminates the danger of breakage to which the dogs and their pivots would be subjected were the weight of the 80 elevator and its contents suddenly thrown on them without the action of a cushion, which permits a vibration of the parts without injury to the locking mechanism.

What is claimed is:—

1. A safety device for elevators including a car having a relatively fixed portion, pivoted gravity acting dogs located at opposite sides thereof, means for slidably mounting the dogs on the car and for cushioning them, and separate means connected with the hoisting mechanism of the car and normally held by the same abutting against the said fixed portion of the car above the dogs and adapted in event of breakage of 90 the hoisting mechanism to be released and to drop into engagement with the dogs for throwing the same outwardly to stop the car, the last mentioned means having a limited downward movement independent 95 of the dogs.

2. A safety device for elevators including a car provided at opposite sides with relatively fixed abutments, pivoted gravity acting dogs located at opposite sides thereof, 105 means for slidably mounting the dogs on the car and for cushioning them, and a cross head connected with the hoisting mechanism of the car and having its terminal portions guided on the car and normally held by the said hoisting mechanism against the fixed abutment of the car at a point above the said dogs and having a limited sliding movement on the car independent of the movement of said dogs, said cross head being adapted in event of breakage of the 110 hoisting mechanism to be released from the same and to drop into engagement with the dogs for throwing the latter outwardly to 115 stop the car.

3. A safety device for elevators including a car provided with a stop or abutment, pivoted gravity acting dogs located at opposite sides of the car, a cross head located above the said dogs and designed to be connected with the hoisting mechanism of the car and arranged to be held against the 125 said stop or abutment by the said hoisting mechanism, said cross head being adapted when released to drop into engagement with 130

the dogs for throwing the same outwardly to stop the car, and a spring normally held under pressure by the cross head and adapted to actuate the same to produce a quick 5 downward movement thereof.

4. A safety device for elevators including a car, dogs located at opposite sides of the car and arranged to be thrown outwardly to stop the same, a cross head located above the 10 dogs and adapted to drop into engagement with the same, a rod secured to the cross head and adapted to be connected with the hoisting mechanism of the car, a spring disposed on the rod and arranged to urge the 15 cross head downwardly to produce a quick movement thereof in event of breakage of the hoisting mechanism, and stops or abutments located at opposite sides of the car and arranged to limit the upward movement 20 of the cross head and adapted to relieve the said spring of the weight of the car.

5. A safety device for elevators including a car provided at opposite sides with guides 25 and having stops or abutments at the upper ends thereof, a cross head designed to be connected with the hoisting mechanism of the car and slideable in the said guides and normally fitting against the said stops or 30 abutments, and dogs mounted on the car independently of the said cross head and located below the same and having portions extending into the path of the cross head and adapted to be engaged thereby to throw 35 the dogs outwardly to stop the car.

6. A safety device for elevators including a car having a relatively fixed portion, vertically slideable members mounted on the car at opposite sides thereof, means for cushioning the said members, dogs mounted 40 on the members, and dog operating means normally held against the said fixed abut-

ment of the car by the hoisting mechanism thereof and adapted to be released in event of breakage of the hoisting mechanism for 45 throwing the dogs outwardly.

7. A safety device for elevators including a car having a relatively fixed portion, independently movable vertically slideable members mounted on the car at opposite sides thereof, separate cushioning means for the said members, gravity acting dogs carried by the said members, and dog operating means connected with the hoisting mechanism of the car and normally held against 55 the said fixed portion of the car at a point above the dogs by the said hoisting mechanism and adapted to be released by the breakage of the same to throw the dogs outwardly. 60

8. A safety device for elevators including a car provided at opposite sides with vertical ways, vertically disposed slides guided in the said ways and provided with openings, dogs pivotally mounted in the openings and movable inward automatically, springs arranged at the upper ends of the slides for cushioning the same, a vertically movable cross head guided on the car and normally located above the dogs and adapted to move downwardly into engagement with the same to throw the dogs outwardly, and means for connecting the cross head with the hoisting mechanism of the car to maintain the cross head normally out of 70 contact with the said dogs. 75

In testimony, that I claim the foregoing as my own, I have hereto affixed my signature in the presence of two witnesses.
